UNITED STATES PATENT OFFICE.

JOHN POULSON, OF PHILLIPSBURG, NEW JERSEY, ASSIGNOR TO THE PHILADELPHIA EXHAUST VENTILATOR COMPANY, OF PENNSYLVANIA.

POWER-ACTUATED FAN.

SPECIFICATION forming part of Letters Patent No. 415,947, dated November 26, 1889.

Application filed June 13, 1889. Serial No. 314,169. (No model.)

To all whom it may concern:

Be it known that I, JOHN POULSON, of Phillipsburg, Warren county, in the State of New Jersey, have invented an Improvement in 5 Power-Actuated Fans, of which the following is a specification.

My invention relates to power-actuated fans; and it consists of certain improvements, which are fully set forth in the following 10 specification, and shown in the accompanying drawings, which form a part thereof.

The object of my invention is to construct a fan in which the air-moving or current-creating blades may be easily adjusted at different angles to change the direction of the air-current and cause the draft to move in a more or less upward or downward direction, as may be desired. The mechanism by which this result is accomplished is illustrated in 20 the drawings, in which—

Figure 1 is a side elevation of a fan embodying my improvements. Fig. 2 is a perspective view of one of the detached blades. Fig. 3 is an inverted plan view of the locking device, on an enlarged scale, with the handle broken off; and Fig. 4 is a side elevation of a modification of the fan shown in Fig. 1.

A is a box or frame, in which the current-creating blades are journaled. This box or 30 frame is secured to the power-shaft B, which is journaled in a suitable support or stationary frame D, and is operated by the power or band wheel C. The box A is formed with an opening E at its central part, and is provided with tubular bearings F opening therein, through which the journals G of the blades H extend. These blades are provided upon 35 their ends within the opening E of the box A with circular gears I, which engage with a pinion J within the box A. This pinion J is carried by a rod K, provided with a handle O of any suitable construction on its end outside of the box A, and has the effect of coupling the blades H together through the circular gears I.

L is a spring acting between the rod K and box A to keep the rod K and its pinion J normally in a raised position. The rod K is provided with a laterally-extending pin or projection N, which is adapted to engage in

notches M, formed on the base of the box A about the opening through which the rod K extends. The spring L normally locks the pin N in one of the notches M, and thus locks the rod K to the box A, and similarly locks 55 the arms or blade H together and to the box A through the action of the pinion and gears. The pinion J is sufficiently long as to never come out of gear by the longitudinal movement of the rod K.

The operation of the device is as follows: When the shaft B is rotated, it carries with it the box A, which is secured to it, and thus rotates the arms or blades H about a vertical axis, which blades, as heretofore explained, 65 are locked together and to the box A by means of the pinion J and the pin N. In order to adjust or change the angles of the blades H, the rod K is drawn down by the handle O, freeing the pin N, so that the rod may be 70 turned. A turning of the rod K turns the pinion J, and, as this pinion gears with the gears I of the blades H, it will correspondingly turn them so as to change the angle of the blades H. It will be seen that these blades 75 will be moved in opposite directions and an equal degree. When the blades are turned to the proper angle, the handle O is released and the spring L instantly returns the rod K to its normal position and the pin N engages 80 with another of the notches M, locking the parts together, as heretofore described. It will be seen that by changing the angles of the blades H the direction of the air-current caused by their motion will be correspondingly changed.

While I prefer the details of construction here shown, I do not limit my invention to them, as it is apparent that they may be modified more or less without departing from the 90 principles of my invention. Thus in Fig. 1 is shown a ceiling-fan, while in Fig. 4 is shown a pedestal-fan supported upon the floor; and it is also evident that the locking-notches and pin might be reversed or placed within the 95 box, as these changes are mere mechanical equivalents.

Having now described my invention, what I claim as new, and desire to secure by Letters Patent, is—

1. In a power-fan, the combination, with the power-shaft, of a journal-box carried thereby, two air-moving blades journaled in said box in line with each other and provided with 5 circular gears upon their inner ends, and a reciprocatable pinion supported by said journal-box and arranged between and gearing with said gears, whereby the angle of said blades may be changed by turning said pinion.
2. In a power-fan, the combination, with the power-shaft, of a journal-box carried thereby, one or more air-moving blades journaled in said box and provided with circular gears 15 upon their inner ends, and a reciprocatable pinion supported by said journal-box and arranged between and gearing with said gears, whereby the angle of said blades may be changed by turning said pinion, and a lock 20 to normally lock said pinion in different positions of adjustment to the journal-box.
3. In a power-fan, the combination, with the power-shaft, of a journal-box carried thereby, one or more air-moving blades journaled in said box and provided with circular 25 gears upon their inner ends, a reciprocatable pinion supported by said journal-box and arranged between and gearing with said gears, whereby the angle of said blades may be 30 changed by turning said pinion, a lock, and a spring device, substantially as described, to normally operate said lock to lock the pinion to the journal-box and permit it to be unlocked for the purpose of shifting the angle 35 of the blades.
4. In a power-fan, a vertical shaft, a rotating journal box or frame carried thereby, two diametrically-opposite fan-blades journaled in said box and having circular gears on their 40 inner ends, a vertically-movable pinion arranged between said gears and gearing with them both, and a shaft to move said pinion up or down, extending below said box and terminating in a handle.
5. In a power-fan, a vertical shaft, a rotating journal box or frame carried thereby, two diametrically-opposite fan-blades journaled in said box and having circular gears on their inner ends arranged transversely to the axis of the blades, a vertically-movable pinion 45 gearing with said gears, a shaft to move said pinion up or down, extending below said box and terminating in a handle, and a spring to force said pinion and shaft upward.
6. In a power-fan, a vertical shaft, a rotating journal box or frame carried thereby, two diametrically-opposite fan-blades journaled in said box and having circular gears on their inner ends arranged transversely to the axis of the blades, a vertically-movable pinion 50 gearing with said gears, a shaft to move said pinion up or down, extending below said box and terminating in a handle, and a spring to force said pinion and shaft upward, and a lock to lock said pinion in any position of rotation upon its vertical axis.
7. In a power-fan, a vertical shaft, a rotating journal box or frame carried thereby, two diametrically-opposite fan-blades journaled in said box and having circular gears on their 55 inner ends arranged transversely to the axis of the blades, a vertically-movable pinion gearing with said gears, a shaft to move said pinion up or down, extending below said box and terminating in a handle, and a spring to force said pinion and shaft upward, and a lock to lock said pinion in any position of rotation upon its vertical axis, and consisting of notches and a pin or projection therefor arranged between the box and shaft of the pinion. 60
